[57] **CLAIM**

The ornamental design for housing for desoldering system mechanism, substantially as shown and described.

DESCRIPTION

FIG. 1 is an isometric view of a housing for desoldering system mechanism embodying my new design, the portions of the cords being shown broken away to indicate indeterminate length;

FIG. 2 is a side elevational view taken from the left of FIG. 1;

FIG. 3 is a rear elevational view thereof;

FIG. 4 is a bottom plan view thereof.
